FORGING PRESS

Edmund A. Skowron, Pittsburgh, and Wilbert H. Woodings, Oakmont, Pa.

Application November 9, 1944, Serial No. 562,702

14 Claims. (Cl. 78—42)

This invention relates to forging presses, and more particularly to the feeding of work to forging dies and the removal of it therefrom.

The splice bars that connect the ends of railroad rails together become worn and hammered out of shape in use. Accordingly, it has been the practice to remove these worn splice bars and to reform them into substantially their original shape by first heating them and then forging them between appropriate dies. Heretofore the general practice has been to place each splice bar between the reforming dies by hand and to remove the reformed bars in the same way. Obviously, this retards the reforming process and requires considerable manual labor.

It is among the objects of this invention to provide a forging press which automatically loads and strips its own dies, which accurately positions the work between the dies, and in which the loading and unloading mechanism is controlled in accordance with the movements of the reciprocating die.

In accordance with this invention a forging press is provided with cooperating top and bottom dies and with a vertically reciprocable head that carries the top die. Suspended from this head are inwardly projecting loading fingers and inwardly projecting unloading fingers located at opposite ends of the dies with the unloading fingers in back of the loading fingers. Means is provided for moving the fingers backward while the head is raised, and forward while it is lowered. While the head is descending, the loading fingers pass down across the ends of the bottom die, and while the head is rising, the unloading fingers pass up across the ends of the same die. Consequently, the loading fingers can lift an unforaged workpiece from a conveyor or the like and then deposit it on the bottom die, and simultaneously the unloading fingers can lift a forged workpiece from the bottom die and then deposit it on a work receiver.

The fingers preferably are carried by a pair of horizontal bars that are suspended pivotally from arms pivotally connected at their upper ends to the reciprocable head. These arms are swung back and forth in cooperation with the vertical movements of the head to move the fingers from one position to another. In order that the full length of the workpiece may be properly forged, the dies preferably are made as long as the workpiece and the lower die is provided in its ends with vertical slots for receiving the vertically moving fingers. When the head is in its lower position the fingers located adjacent the lower die

are disposed below the slots in a laterally open space which permits them to be moved laterally toward or away from the die.

The preferred embodiment of the invention is illustrated in the accompanying drawings in which Fig. 1 is a side view, partly broken away, of a forging press provided with our feeding mechanism; Fig. 1a is a fragmentary side view showing the feeding mechanism in its lower rear position; Fig. 2 is an enlarged fragmentary view of the rear end of the feed mechanism taken on the line II—II of Fig. 1; Fig. 3 is a horizontal section taken on the line III—III of Fig. 2; and Fig. 4 is an enlarged side view of a modified loading or unloading finger assembly.

Referring to Fig. 1 of the drawings, a bed 1 supports a die holder 2 in which is mounted a lower die 3 for forging articles, for example, for reforming splice bars. Mounted on the base flange of the bed at opposite sides thereof is a pair of side frames 4, each in the form of two laterally spaced vertical columns integrally connected together at their upper and lower ends. These side frames support a chambered crown 6 which is held in place by heavy tie rods 7 that extend through the crown, side frame columns, and the base flange of the bed.

Disposed between the side frames above the bottom die is a vertically reciprocable slide 8 that is held in place by the side frames. In order to support this slide in an elevated position, an open-top hydraulic cylinder 9 is rigidly mounted in each side of the crown and projects downwardly a short distance through an opening 11 (Fig. 3) in the top of the underlying side frame. Disposed in these lifting cylinders are pistons 12 which have piston rods 13 extending from their lower ends through the bottoms of the cylinders and into brackets 14 by which they are connected to the opposite sides of the slide. The lower end of each cylinder is connected by a pipe 16 to a source of hydraulic pressure, whereby the application of pressure elevates the pistons in the cylinders and holds the slide in its upper position until the pressure is released.

Upon release of pressure from the cylinders, the slide descends until the upper die 17 connected to its lower end engages a red hot splice bar resting on the lower die. Pressure is then applied to the slide to cause the dies to press the splice bar back into shape. The application of the forging pressure is effected through a ram 18 mounted on top of the slide and extending upwardly into a downwardly opening cylinder 19 formed in the center of the crown. The ram and slide together

form a reciprocable head. Hydraulic pressure is applied to the top of the ram inside the cylinder through a pipe 21 communicating with an opening in the top wall of the cylinder. When this pressure is released, the head can be raised by applying hydraulic pressure to the lifting cylinders 8 as mentioned above.

It is a feature of this invention that, as the head moves up and down, splice bars automatically are lifted from a feeder and placed upon the lower die, reformed, stripped from the dies, and deposited on some kind of a receiver such as skids by which they may be delivered to a quenching tank. Accordingly, a pair of brackets 25 are rigidly attached to each side of the slide near its bottom and project down below it. The lower ends of these brackets rotatably support the ends of a pair of parallel shafts 26 which extend across the slide near its front and back. Splined on each shaft are the upper ends of a pair of parallel arms 27 straddled by yokes 28 provided on top with projections 29 having threaded openings through them parallel to the shaft. Threaded in each of these openings is a horizontal screw 31 disposed in a recess in the bottom of the slide and extending out through the adjacent bracket 25. A sprocket 32 is rigidly mounted on the projecting outer end of each screw, and the pair of sprockets at each side of the slide are connected by a chain 33. Also, a hand wheel 34 is rigidly mounted on the outer end of one of the screws at each side of the slide. By turning the hand wheels the four screws are rotated in order to move yokes 28 along them to thereby adjust arms 27 along shafts 26 for a purpose to be described later.

Pivotedly connected to the lower ends of the two arms at each side of the slide is a horizontal bar 36 near the opposite ends of which inwardly projecting lugs or fingers are mounted. The front fingers 37 are loading fingers and the rear ones 38 are unloading fingers. The arms are provided near their upper ends with lateral projections in which stop screws 39 are adjustably mounted. These screws, by engaging the bottom of the slide, limit the distance that the arms can be swung either forward or backward. The stops are so adjusted that in either extreme position of the arms a pair of the fingers will lie in a vertical plane extending through the center of the dies longitudinally thereof.

For swinging the arms, a rearwardly and downwardly projecting lever 41 is rigidly mounted on the central portion of the rear shaft 26. The lower end of this lever is pivotally connected by a link 42 to the front end of another lever 43 that is pivotally supported at its center by a bracket 44 projecting from the back of the slide. The rear end of this lever is pivotally connected to the lower end of a piston rod 46 projecting from a piston in a hydraulic cylinder 47 which is pivotally connected at its upper end to the back of the slide. When hydraulic pressure is applied to the lower end of this cylinder, the piston rod 46 is drawn up into it, thereby swinging arms 27 to their front position as shown in Fig. 1. When pressure is applied to the upper end of the cylinder the piston therein is forced downwardly to thereby, through levers 41 and 43, swing the arms to their rear position shown in Fig. 1a.

Assuming that the movable parts of the press are in the position shown in Fig. 1 and that an unformed splice bar 48 is resting on loading fingers 37 while a bar 49 that has just been reformed

is supported by the unloading fingers 38, the press may be set in operation by turning a valve or pressing an electric control button (not shown). This action operates a four-way valve 50 through which oil under pressure flows to the upper end of cylinder 47 while oil escapes from the lower end of the cylinder. The pressure in the cylinder moves the piston therein downwardly and thereby causes levers 43 and 41 to swing arms 27 of the feed mechanism toward the back of the press. The stop screws 39 on the arms will stop them in the dotted line position shown in Fig. 1 with the loading fingers then centered above the lower die. The tilting of lever 43 swings an actuating element 51, operatively connected thereto, to close an electric switch 52 that operates a four-way valve 53, connecting pipes 16 and 21 to a source of hydraulic pressure, to release the pressure from the lower ends of cylinders 8 and to admit hydraulic pressure to the top of main cylinder 19. The head then slides down slowly and the loading fingers deposit the unformed splice bar 48 on the lower die while the unloading fingers deposit the reformed bar 49 on delivery skids 54 as shown in Fig. 1a.

In order that the lower die may be as long as the splice bars, its opposite ends are provided centrally with vertical slots 55 to accommodate fingers 37 and 38 which, of course, extend inwardly along the splice bars. As shown in Fig. 2, the lower die is longer than its holder 2 so that there will be an open space below it that will permit the lowered fingers to move laterally toward and away from the bottoms of slots 55 as bars 36 are swung toward the front of the press.

As soon as the upper die engages the splice bar resting on the lower die the hydraulic pressure admitted to the top of cylinder 19 in the crown starts to build up and the dies press the bar into the desired shape. When the pressure reaches a predetermined value a pressure switch 56 connected to pipe 21 is tripped and, through suitable conventional means, shifts valve 50 so that fluid under pressure will be admitted to the lower end of cylinder 47 while the upper end of the cylinder is vented. This causes lever 43 to be swung back to the position shown in Fig. 1 and to thereby swing bars 36 toward the front of the press to the dotted line position shown in Fig. 1a. At the same time pressure switch 56 also causes valve 53 to be shifted to a neutral position in which the pressure in cylinder 19 is released. Tilting of lever 43 permits switch 52 to open and, through another actuating element 57, closes another electric switch 58 when bars 36 complete their forward stroke. Switch 58 causes valve 53 to move from neutral position into a position that connects cylinders 8 with the source of hydraulic pressure so that pistons 12 will start to rise and thereby lift the head and the loading mechanism. As loading fingers 37 rise they lift the next unformed splice bar from entry skids 59, and unloading fingers 38 pass up through slots 55 in the ends of the lower die and lift from it the bar that has just been forged on it. The head and the loading mechanism are then back in the position shown in Fig. 1, ready to repeat the cycle just described. When it is desired to forge splice bars of a different length, hand wheels 34 can be turned to change the spacing between bars 36 accordingly.

In Fig. 4 there is shown a work-carrying finger, a pair of which may be used in place of the loading fingers 37, and an additional pair substituted for the unloading fingers if desired. These new

fingers are designed to center the splice bars between bars 36 so that they will rest evenly on the lower die and not project from either end. For this purpose a bracket 61 is adapted to be mounted on one of the bars 36 and is provided in its lower portion with a recess 62 extending transversely through it. Extending across the outer end of this recess is a pin 63, and pivotally mounted on this pin is one end of a finger 64. The finger extends through the recess and projects from its inner end. The projecting end of the finger, which can be swung up and down in the recess, has a substantially horizontal surface 66 on which the end of a splice bar can rest, and a substantially vertical surface 67 adapted to bear against the bar's end surface or the upper edge of that surface. The finger normally is held in its upper dotted line position by means of a coil spring 68 encircling a vertical rod 69 that extends down through a passage in the bracket and into a slot in the finger in which it is pivotally connected to the finger by a pin 71.

When a pair of these fingers rise into contact with a splice bar that is to be forged, the weight of the bar will tend to swing the fingers downwardly in bracket recesses 62. However, if the bar is the longest that the press is set for at the time, the ends of the bar will engage vertical surfaces 67 of the fingers, as well as horizontal surfaces 66, and thereby prevent them from swinging down. In case the splice bar is shorter, neither end may engage vertical surfaces 67 initially, so the fingers will be depressed by the bar until those surfaces strike its opposite ends as shown in full lines in Fig. 4, or until the fingers are arrested by their supporting bars 36. In many cases, however, a short splice bar will not be centered between the fingers when first picked up, but will be closer to the vertical surface 67 of one than the other. When the fingers start to swing down, one of them will therefore push the splice bar toward the other until it is centered between them with both of its ends engaged by the vertical surfaces 67 of the fingers. The fingers therefore automatically center the splice bars, regardless of their length.

These fingers can also be used as stripping or unloading fingers, but for a different reason. It will be seen that the fingers tend to push the bar supported by them toward each other, and they therefore clamp it between them and hold it steady. This feature may be important in lifting forged bars from the bottom die and carrying them to the delivery skids.

With this apparatus the splice bars are fed through the press automatically and at a more constant rate than was possible when the feed was manual. After the press has been started in operation it will complete a cycle without attention, and the successive cycles can be made to follow each other automatically by merely locking in the starting device in a well-known manner, thus making the press fully automatic.

According to the provisions of the patent statutes, we have explained the principle and construction of our invention and have illustrated and described what we now consider to represent its best embodiment. However, we desire to have it understood that, within the scope of the appended claims, the invention may be practiced otherwise than as specifically illustrated and described.

We claim:

1. A forging press comprising cooperating top

and bottom dies, a vertically reciprocable head carrying the top die, an inwardly projecting loading finger and an inwardly projecting unloading finger disposed at each end of the dies with the unloading fingers behind the loading fingers, means suspending said fingers from said head, and means for moving said fingers backward while the head is raised and forward while it is lowered, said loading fingers passing down across the ends of the bottom die while the head is descending, and said unloading fingers passing up across the ends of the bottom die while the head is rising, whereby an unformed workpiece may be lifted by the loading fingers from a feeder and then deposited on the bottom die, and a forged workpiece lifted by the unloading fingers from the bottom die and then deposited on a receiver.

2. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, means suspending said fingers from said head, and means for moving said fingers backward while the head is raised and forward while it is lowered, each end of the bottom die being provided with a vertical slot terminating at its lower end in a laterally open space, said loading fingers passing down through said slots while the head is descending, and said unloading fingers passing up through said slots while the head is rising, whereby an unformed workpiece may be lifted by the loading fingers from a feeder and then deposited on the bottom die, and a forged workpiece lifted by the unloading fingers from the bottom die and then deposited on a receiver.

3. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, means suspending said fingers from said head, means for moving said fingers backward while the head is raised and forward while it is lowered, and means controlled by said movements of the fingers for lowering and raising the head, said loading fingers passing down across the ends of the bottom die while the head is descending, and said unloading fingers passing up across the ends of the bottom die while the head is rising, whereby an unformed workpiece may be lifted by the loading fingers from a feeder and then deposited on the bottom die, and a forged workpiece lifted by the unloading fingers from the bottom die and then deposited on a receiver.

4. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, vertically extending arms pivotally connected at their upper ends to said head for oscillation in parallel vertical planes at the opposite ends of the dies, means connecting said fingers to the lower ends of the arms, and means for swinging said arms backward while the head is raised and forward while it is lowered, said loading fingers passing down across the ends of the bottom die while the head is descending, and said unloading fingers passing up across the ends of the bottom

die while the head is rising, whereby an unformed workpiece may be lifted by the loading fingers from a feeder and then deposited on the bottom die, and a forged workpiece lifted by the unloading fingers from the bottom die and then deposited on a receiver.

5. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, vertically extending arms pivotally connected at their upper ends to said head for oscillation in parallel vertical planes at the opposite ends of the dies, means connecting said fingers to the lower ends of the arms, a fluid pressure cylinder connected to said head, and means operatively connecting said cylinder to said arms for swinging the arms backward while the head is raised and forward while it is lowered, said loading fingers passing down across the ends of the bottom die while the head is descending, and said unloading fingers passing up across the ends of the bottom die while the head is rising, whereby an unformed workpiece may be lifted by the loading fingers from a feeder and then deposited on the bottom die, and a forged workpiece lifted by the unloading fingers from the bottom die and then deposited on a receiver.

6. A forging press comprising cooperating top and bottom dies, a vertically reciprocable head carrying the top die, a pair of horizontal bars disposed in parallel vertical planes at the opposite ends of the dies, means suspending each bar from said head for lengthwise movement, a loading finger projecting inwardly from the front end of each bar, an unloading finger projecting inwardly from the rear end of each bar, each end of the bottom die being provided with a vertical slot terminating at its lower end in a laterally open space, and means for swinging said bars backward while the head is raised and forward while it is lowered, said loading fingers passing down through said slots while the head is descending, and said unloading fingers passing up through said slots while the head is rising, whereby an unformed workpiece may be lifted by the loading fingers from a feeder and then deposited on the bottom die, and a forged workpiece lifted by the unloading fingers from the bottom die and then deposited on a receiver.

7. A forging press comprising cooperating top and bottom dies, a vertically reciprocable head carrying the top die, a pair of horizontal bars disposed in parallel vertical planes at the opposite ends of the dies, a pair of arms at each end of the dies pivotally connected to said head and to the opposite ends of the underlying bar, means for swinging the arms backward while the head is raised and forward while it is lowered, a loading finger projecting inwardly from the front end of each bar, an unloading finger projecting inwardly from the rear end of each bar, each end of the bottom die being provided with a vertical slot terminating at its lower end in a laterally open space, said loading fingers passing down through said slots while the head is descending, and said unloading fingers passing up through said slots while the head is rising, whereby an unformed workpiece may be lifted by the loading fingers from a feeder and then deposited on the bottom die, and a forged workpiece lifted by the unloading fingers from the bottom die and then deposited on a receiver.

8. A forging press comprising cooperating top and bottom dies, a vertically reciprocable head carrying the top die, a pair of horizontal bars disposed in parallel vertical planes at the opposite ends of the dies, a pair of arms at each end of the dies pivotally connected to said head and to the opposite ends of the underlying bar, a lever operatively connected to the arms, fluid pressure actuated means carried by said head and operatively connected to said lever for actuating it to swing the arms backward while the head is raised and forward while it is lowered, a loading finger projecting inwardly from the front end of each bar, an unloading finger projecting inwardly from the rear end of each bar, each end of the bottom die being provided with a vertical slot terminating at its lower end in a laterally open space, said loading fingers passing down through said slots while the head is descending, and said unloading fingers passing up through said slots while the head is rising, whereby an unformed workpiece may be lifted by the loading fingers from a feeder and then deposited on the bottom die, and a forged workpiece lifted by the unloading fingers from the bottom die and then deposited on a receiver.

9. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, means suspending said fingers from said head, means for moving said fingers backward while the head is raised, and means controlled by the pressure of the top die against a workpiece for moving said fingers forward while the head is lowered, said loading fingers passing down across the ends of the bottom die while the head is descending, and said unloading fingers passing up across the ends of the bottom die while the head is rising, whereby an unformed workpiece may be lifted by the loading fingers from a feeder and then deposited on the bottom die, and a forged workpiece lifted by the unloading fingers from the bottom die and then deposited on a receiver.

10. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, means suspending said fingers from said head, means for moving said fingers backward while the head is raised, and means controlled by the pressure of the top die against a workpiece for moving said fingers forward while the head is lowered, and means controlled by said movements of the fingers for lowering and raising the head, said loading fingers passing down across the ends of the bottom die while the head is descending, and said unloading fingers passing up across the ends of the bottom die while the head is rising, whereby an unformed workpiece may be lifted by the loading fingers from a feeder and then deposited on the bottom die, and a forged workpiece lifted by the unloading fingers from the bottom die and then deposited on a receiver.

11. A forging press comprising top and bottom dies, a vertically reciprocable head carrying the top die, a pair of parallel shafts extending across the bottom of the head near its front and rear sides, means rotatably supporting said shafts from the head, a pair of laterally spaced arms splined at their upper ends on each shaft, man-

ually operable means for adjusting said arms along the shafts, a pair of horizontal bars disposed in parallel vertical planes at the opposite ends of the dies, each bar being pivotally connected to the lower ends of the arms beside it, means connected to one of said shafts for oscillating it to swing said bars backward in said planes while the head is raised and forward while it is lowered, a loading finger projecting inwardly from the front end of each bar, an unloading finger projecting inwardly from the rear end of each bar, said loading fingers passing downwardly across the ends of the bottom die while the head is descending, and said unloading fingers passing up across the ends of the bottom die while the head is rising, whereby an unforged workpiece may be lifted by the loading fingers from a feeder and then deposited on the bottom die, and a forged workpiece lifted by the unloading fingers from the bottom die and then deposited on a receiver.

12. A forging press comprising top and bottom dies, a vertically reciprocable head carrying the top die, a pair of parallel shafts extending across the bottom of the head near its front and rear sides, means rotatably supporting said shafts from the head, a pair of laterally spaced arms splined at their upper ends on each shaft, a screw threadably connected to the upper end of each arm and extending outwardly along the adjacent shaft, means operably connecting the outer ends of the pair of screws at each side of the head for manual rotation in unison to adjust said arms along the shafts, a pair of horizontal bars disposed in parallel vertical planes at the opposite ends of the dies, each bar being pivotally connected to the lower ends of the arms beside it, means connected to one of said shafts for oscillating it to swing said bars backward in said planes while the head is raised and forward while it is lowered, a loading finger projecting inwardly from the front end of each bar, an unloading finger projecting inwardly from the rear end of each bar, said loading fingers passing downwardly across the ends of the bottom die while the head is descending, and said unloading fingers passing up across the ends of the bottom die while the head is rising, whereby an unforged workpiece may be lifted by the loading fingers from a feeder and then deposited on the bottom die, and a forged workpiece lifted by the unloading fingers from the bottom die and then deposited on a receiver.

13. A forging press comprising cooperating co-
operating top and bottom dies, a vertically re-

ciprocable head carrying the top die, an inwardly projecting loading finger and an inwardly projecting unloading finger disposed at each end of the dies with the unloading fingers behind the loading fingers, means suspending said fingers from said head, the outer ends of said loading fingers being pivotally mounted on horizontal axes and their inner ends having substantially horizontal work-supporting surfaces with substantially vertical work-engaging surfaces rising therefrom for centering a workpiece between the loading fingers, means biasing said inner ends of the pivoted fingers upwardly, and means for moving said fingers backward while the head is raised and forward while it is lowered, said loading fingers passing down across the ends of the bottom die while the head is descending, and said unloading fingers passing up across the ends of the bottom die while the head is rising, whereby an unforged workpiece may be lifted by the loading fingers from a feeder and then deposited on the bottom die, and a forged workpiece lifted by the unloading fingers from the bottom die and then deposited on a receiver.

14. A forging press comprising cooperating top and bottom dies, a vertically reciprocable head carrying the top die, an inwardly projecting loading finger and an inwardly projecting unloading finger disposed at each end of the dies with the unloading fingers behind the loading fingers, means suspending said fingers from said head, the outer ends of said loading fingers being pivotally mounted on horizontal axes and their inner ends having substantially horizontal work-supporting surfaces with substantially vertical work-engaging surfaces rising therefrom for centering a work-piece between the loading fingers, a vertical rod pivotally connected at its lower end to each pivoted finger, and a coil spring encircling each rod and compressed thereon for urging the rod and underlying finger upwardly, and means for moving said fingers backward while the head is raised and forward while it is lowered, said loading fingers passing down across the ends of the bottom die while the head is descending, and said unloading fingers passing up across the ends of the bottom die while the head is rising, whereby an unforged workpiece may be lifted by the loading fingers from a feeder and then deposited on the bottom die, and a forged workpiece lifted by the unloading fingers from the bottom die and then deposited on a receiver.
